J. A. DE CEW.
ATTACHMENT TO BEATING ENGINES.
APPLICATION FILED APR. 18, 1919.

1,377,616.

Patented May 10, 1921.

UNITED STATES PATENT OFFICE.

JUDSON A. DE CEW, OF NEW YORK, N. Y., ASSIGNOR TO PROCESS ENGINEERS, INCORPORATED, OF NEW YORK, N. Y.

ATTACHMENT TO BEATING-ENGINES.

1,377,616.

Specification of Letters Patent.

Patented May 10, 1921.

Application filed April 18, 1919. Serial No. 291,031.

To all whom it may concern:

Be it known that JUDSON A. DE CEW, a subject of the King of Great Britain, and native of the Dominion of Canada, residing 5 at New York city, New York, has invented a new and useful Improvement in Attachments to Beating-Engines, of which the following is a specification.

This invention relates to attachments to 10 beating engines and the object thereof is to greatly increase the efficiency of beating engines already in use by the application thereof of relatively simple attachments, and with this object in view, the invention consists essentially in deflecting plates, having 15 a concave face next to the beating roll of the engine, and located on each side of the roll.

The invention is illustrated in the accompanying drawing in which Figure 1 shows 20 a plan view of a beating engine with the attachments of the invention in place.

Fig. 2 shows a partial vertical section taken along the lines 2—2 in Fig. 1.

Fig. 3 is a view similar to Fig. 2 except 25 that it is an enlarged view of the roll and its attachments.

Fig. 4 is a plan view of a detail.

In the drawings, the numeral 11 represents 30 the vat of the beating engine, 12 the mid-feather, 13 the beating roll, 14 the knives on the roll, 15 the guard over the roll, and 16 the backfall. 17 indicates stock in the beater and 17' the stationary blades under 35 the roll. So much is of ordinary construction and it is to devices of the character just described that my invention will be applied.

In advance of the beater, I propose to 40 locate a deflecting element 18, substantially crescent-shaped in cross-section, with its concave face adjacent the beating roll 13. This deflector extends entirely across the face of the beating drum (or beater) and is 45 adjustably supported at one end to the side wall 19 of the vat and at the other end to the side of the midfeather 12. It must be adjustably supported to allow for the usual vertical adjustment of the roll. One method to so support the deflector is to provide lugs 50 or bosses 20 which may be squared, to the ends of the deflector and to have them coact with grooveways 21 provided on the side and midfeather of the vat respectively. As these grooveways would be open at the top, 55 the deflector could be easily removed there-

from. 22 indicates one or more stops to positively prevent pivotal movement of the deflector sufficiently to have its upper edge engage the knives of the roll.

23 indicates a further deflector extending 60 all the way across the rear of the roll and also having a concave face adjacent to the roll. 24 and 25 indicate angular faces of the deflector which in this case are preferred to the crescent shape of the front deflector. 65 This deflector is adjustably supported similar to the front deflector and the description of the supporting elements 20', 21' and 22' are identical with 20, 21 and 22.

26 represents a secondary doctor for the 70 roll and the lower edge 27 of the rear deflector a primary doctor. It is preferable that the front deflector 18 lie almost wholly below the level of the stock 17 in the vat.

In beating engines at present in use, it is 75 desired to have the stock pass under the roll so that the purpose of the revolving roll is to carry the stock longitudinally along the bottom of the vat past the stationary knives under the roll but I find that the knives 80 of the roll in descending engage the upper portion of the stock and give it a downward movement as only the knives near the bottom of the vat give it the desired horizontal movement. This downward or vertical 85 movement given some of the stock causes eddies and otherwise seriously interferes with the stock flowing horizontally besides requiring an unnecessary amount of power to rotate the roll. In other words, all force 90 used by the blades in imparting vertical movement to some of the stock is lost so far as useful result is concerned. Accordingly, if my front deflector 18 is placed quite 95 closely before the roll, as it can be because the curvature of its concave face is less than the curvature of the roll, it prevents the stock from coming into contact with the blades of the roll until they have reached such an angle in relation to the stock that 100 they will act upon it only longitudinally of the vat.

The rear deflector acts as a doctor at 27 and otherwise assists in keeping the stock away from the blades of the roll after it 105 has once passed thereunder. The secondary doctor 26 will strip from the roll any stock that escaped by the primary doctor 27 and it will fall back along the angular face 24 of the deflector.

What I claim is:—

1. In a beating engine, in combination, a vat, a roll, guideways within the vat having their lower ends closed, and a deflector supported upon the closed lower ends of said guideways.
  2. In a beating engine, in combination, a vat, a roll, vertically disposed guideways within said vat, and a deflector supported by 10 said guideways and having a concave face adjacent said roll.
  3. In a beating engine, in combination, a vat, a roll, vertically disposed guideways within said vat having open upper ends and 15 closed lower ends, and a deflector having lateral projections extending within said guideways and engaging the lower closed
- ends thereof, said deflector having a concave face adjacent said roll.
4. In a beating engine, in combination, a vat, a roll, and a deflector pivotally supported within said vat.
  5. In a beating engine, in combination, a vat, a roll, a deflector pivotally supported within said vat, and means independent of 25 the supporting means for limiting the movement of said deflector.

In testimony whereof, I, the said JUDSON A. DE CEW have signed my name to this specification in the presence of a subscribing 30 witness, this 16th day of April 1919.

JUDSON A. DE CEW.

Witness:

MARSHALL CLARK.
